LABEL HOLDER

Edwin S. Roscoe, Rochester, N. Y., assignor to
Yawman & Erbe Mfg. Co., Rochester, N. Y., a
corporation of New York

Application January 7, 1932. Serial No. 585,273

14 Claims. (Cl. 40—16)

This invention relates to filing or storage devices, and more particularly to label or card holders forming a part of such devices.

In the past it has been the most general practice to rivet label holders on the fronts of drawers or receptacles used in the filing of records, but such label holders are monotonously similar in appearance, they are often too conspicuous, they present obstructions to catch clothing and dust cloths, they are frequently not in harmony with the flush finished surface of a high grade cabinet or surrounding furniture and since they are not resilient, labels occasionally stick in them, causing difficulty in the insertion or removal thereof.

In accordance with the present invention, it is proposed to employ a type of label holder in which the label is mounted behind a window in the front surface of the drawer, cabinet or other receptacle, so that the label holder itself is invisible from the front surface when the label is in place.

An additional feature of the invention relates to a label holder into which the label is inserted preferably from some point at the rear of the front plane of the drawer or receptacle. A further feature of the invention relates to a label holder for use in connection with a sheet metal drawer or receptacle front having an opening therein, which label holder is attached to the lining of the front in such a manner that the label is firmly held against the edges of the mentioned opening. A still further feature of the invention relates to the flexibility of the label holder which insures a snug fit of the label against a substantial portion of the window opening in the receptacle front regardless of the thickness of the label, and at the same time permits the label holder to be pressed backward if necessary, to facilitate the insertion or the removal of the label.

For a clearer understanding of the invention, reference is made to the drawings, in which Fig. 1 is a perspective view of a filing cabinet having three drawers, each of which is provided with a label holder of the present invention; Fig. 2 is a sectional view of a drawer front taken on the line 2—2 of Fig. 1 with a portion thereof broken away; Fig. 3 is a horizontal sectional view of a drawer front taken on the line 3—3 of Fig. 1 with portions thereof broken away; Fig. 4 is a perspective view of a fragment of the drawer front with a label holder shown in operative relation thereto, said label holder being represented as mounted on the drawer liner; Figs. 5 and 6;

Figs. 7 and 8; and Figs. 9 and 10 represent modified forms of the invention, showing respectively vertical and horizontal sections through a portion of the receptacle front, the label holder and the liner.

Referring especially to Fig. 1, 5 designates a sheet metal filing cabinet of any well-known construction, having three compartments arranged in vertical relation to receive filing receptacles or drawers 6. Each drawer includes a drawer front 7 preferably formed of sheet metal and having a rectangular opening 8 stamped therein with the material adjacent the opening rolled backward so that the edges 9 of the material at the opening are substantially parallel with the plane of the drawer front. It will be noted from Figs. 2 and 3, that the material at the edges of the drawer front is bent backward to engage a reinforcing lining 10 (sometimes referred to as a liner) which is spaced a short distance from the drawer front and forms therewith a hollow chamber. While the edges of the drawer front may be attached to the edges of the lining in various ways well-known in the art, the mounting arrangement of these members shown in Figs. 2 and 3 has been found to be especially satisfactory. At the top of the drawer front, the sheet material is bent backward to form a rectangular portion 11 which in turn is provided with an extension strip 12 extending downwardly parallel to the drawer front. The material at the bottom of the drawer is formed to have a portion 13 extending rearwardly from the drawer front and at right angles thereto, which portion has an integral part 14 extending upwardly parallel to the drawer front. The part 14 is provided at its upper edge with an integral strip 15 extending at right angles to the drawer front to engage the sheet material 16 forming the bottom of the drawer. This strip may be attached to the drawer bottom by spot welding, or by any other suitable means.

The material at each side of the drawer front is formed to have a portion 17 extending rearwardly at right angles to the drawer front and an integral part 18 extending inwardly from the portion 17 to the side 19 of the drawer. The part 18 of the drawer front has an integral strip 20 extending rearwardly in engagement with the drawer side 19 to which it may be attached by spot welding or by any other suitable means.

In order to give rigidity to the drawer and to the drawer front, the lining 10 is mounted in spaced relation to the drawer front 7. While the invention is not limited to the details of mount-

- ing the lining with respect to the drawer front, the arrangement herein disclosed has been found to be especially satisfactory. The bottom and side edges of the lining are provided with rectangular flanges 21, 22 and 23, which respectively engage the sides 19 of the drawer and the bottom 16 thereof, while the free edges of these flanges engage the rear surface of the drawer front. The material at the top of the lining is formed with a rectangular portion 24 which is bent forward to engage the front of the drawer, and with an integral angular portion 25, the free edge of which engages the corner defined by the portions 11 and 12 of the top of the drawer front.
- 15 The lining may be assembled into the receptacle front 7 by inserting the edge of the angular portion 25 at the top of the liner into the corner defined with portions 11 and 12 at the top of the drawer front, while the lower edge of the lining is held at a position by the nuts and bolts 4 which hold the drawer pull 3 in position. It will be understood that with this construction and mounting, the drawer front 7 and the lining 10 define a hollow compartment closed at its sides.
- 20 25 The upper horizontal portion 24 of the lining is provided with a slot 26 of sufficient length to receive a label 27 which may be inserted therethrough into position behind the window 8. The label, when thus inserted, is supported behind this window by a label holder 28 which is provided on three sides with marginal flanges such as 29 and 30 which are bent toward the rear face of the drawer front adjacent the edges of the window opening 8. This label holder may be supported in any suitable manner in the position herein shown, but it has been found convenient to mount it resiliently on the lining 10. This mounting construction includes an inclined portion 31 which serves to guide the label into the label holder 28, and an attaching strip 32 integral with the portion 31 and extending into engagement with the front surface of the lining 10 to which it is attached as indicated at 33 by any suitable means, such as, by spot welding.
- 35 40 45 50 55 60 65 70 75 The label holder is also provided with a rear wardly extending flange 34 which serves to give partial rigidity to the lower edge of the label holder and functions as a stop when its rear edge engages the lining 10 as the operator springs back the label holder in order to facilitate the insertion and removal of the label.
- From the foregoing description, it will be understood that the label 27 is preferably inserted from the rear of the drawer front, such as by inserting it through the slot 26 while the inclined portion 31 of the label holder guides the label into the holder where it is held in close engagement with the edges 9 of the rolled material of the drawer front which define the window opening 8.
- In the modified form of the invention shown in Figs. 5 and 6, the lining 10 is itself shaped to form a label holder for holding the label behind the window 8 in the receptacle front 7. In this arrangement the lining has formed integrally therewith, the label holding panel 38 which is joined to the principal plane 39 of the lining by inclined portion 40 which serves as a guide for inserting the label, while the other sides of this panel may be joined to the principal plane of the liner by inclined portions 42, 43 and 44. While the portions 42, 43 and 44 are shown as plane surfaces, they may also be of curved form as is most expedient. At the sides of the label holding panel 38, there are provided lugs 45, 46 and 47 struck out from the material of the inclined portions 42, 43 and 44 respectively, which lugs are bent toward the receptacle front 7 and surround a portion of the window 8. In order to give a flexible mounting for the label holding panel 38, so that the label may be pressed firmly against the edges 9 of the window and yet permit this panel to be pressed away from the receptacle front to facilitate the insertion and the movement of the label, the lining 10, itself can be made, and usually is, sufficiently yielding to serve this purpose.
- In the arrangement shown in Figs. 7 and 8, the receptacle front 7 while it is likewise provided with a window 8 as in the foregoing arrangements, has its window bordered by window frame 49 which is held in place in any suitable manner. This frame may be of any desired material, but it is preferably formed of ornamental bronze to present a decorative effect. It will be understood that the window frame 49 may likewise be employed with any of the other forms of the invention herein disclosed.
- Also in this form of the invention the lining 10 is provided with a window 50 which is in registry with the window 8 when the lining and front member are assembled in position for use. The material of the lining adjacent the window 50 is in the form of curved portions 51, 52, 53 and 54 so that the two mentioned windows are in close operative relation. In this form of the invention this label holder 55 has flanges 56, 57 and 58 having a side and bottom edges connected by the flanges 56, 57 and 58 attached to the curved portions 53, 54 and 55 respectively. These flanges are preferably connected at a slight distance from the window edges of these curved portions so that a label receiving pocket 59 is provided at three sides of the window 50. It is desirable to have the inner margin of the window frame 49 preferably extend to the inner edge of the window 50 as herein shown, although this arrangement is not essential to the invention. In this arrangement, the label is inserted into the label holder through the space between the lining portion 51 and the upper edge of the holder 55. The flanges of the label holder 55, instead of being bent toward the front as shown at 56, 57, and 58, may be simply curved to fit the portions of the liner 52, 53, and 54; while the desired label receptacle 59 can be obtained by flanging the marginal sides and bottom edges of the window 50 to retain the label in registration with the window frame 49. Also in the modifications described above, the liner can be made sufficiently yielding to furnish the degree of flexibility desired for facilitating the insertion and the removal of label and at the same time to hold the label snugly against the edges of the window frame 49. While the label holder of this modification is mounted on the rear face of a portion of the lining 10 as a result of the bending of a portion of the lining toward the receptacle front, still the label holder is mounted between the principal planes of the receptacle front and the lining.
- In the modified form of the invention shown in Figs. 9 and 10, the label holder 60 is provided with flanges 61, 62 and 63 which are respectively fastened to the receptacle front 7 adjacent the window 8 by spot welding or other suitable means. In this form of the invention, a label-receiving slot 64 is provided in the flange forming the upper edge of the front member 7, an arrangement

which is applicable to all of the previously described forms of the invention.

While the method of assembling and fastening the lining with respect to receptacle front 7 has not been disclosed in connection with these last mentioned modifications, it may be similar to that shown in Figs. 2 and 3, although any well-known form of receptacle front and lining construction may be used with any of the forms of the invention.

The construction herein disclosed, is the preferred forms of the invention, but it will be understood that it includes all types of receptacle label holders wherein the label is supported behind

15 a window in the receptacle front. While the "liner" or lining has been shown to be co-extensive with the area of the drawer front, and has been shown with its edges in engagement with the edges of the material of the drawer front, the invention is not so limited, but in fact, the liner may be omitted entirely or may be co-extensive with only the upper portion of the drawer front, or the edges of the lining may be spaced from the edges of the drawer front in 25 any manner found to be most feasible. The slot for inserting or removing the label may be located in the side or bottom edges of the drawer front or liner as well as at the top as shown, or the label may be inserted or removed at the rear 30 of the lining as shown in Fig. 7. Furthermore, it is not essential for the label to extend through one of the flanges forming the edges of the front and liner as shown in the various arrangements or for the label to extend even beyond the body 35 portion of the label holder.

What I claim is:

1. In an article of the class described, a receptacle front member having a window opening therein, a lining member substantially co-extensive with said front wall member, and means 40 between the principal planes of said members for holding a label behind said window opening, said means normally tending to move said label toward said window opening.

45 2. In an article of the class described, a front wall member having a window opening therein defined by an inwardly extending marginal flange, and a label holder supported adjacent said window opening, said label holder having a marginal flange projecting in the direction of said window flange and surrounding at least a portion of the same.

50 3. In an article of the class described, a sheet-metal receptacle front provided with a window opening therein at a substantial distance from the top of said front, and a label holder for supporting a portion of a label against the material of said front member, said label holder being provided with a label guide extending to a point 55 near the edge of said receptacle front.

55 4. In an article of the class described, a front wall member provided with a window opening therein, a lining member for said front wall member mounted in spaced relation thereto, a label holder mounted between said members to support a label behind said window opening, said label holder at one edge being provided with a flange extending adjacent to said window opening and at its opposite edge with a label guide 65 extending to said lining member.

70 5. In an article of the class described, a receptacle front member provided with a window opening, a lining member forming a compartment with said front member, one of said members being provided with a label-receiving slot at one

side of said opening, a label holder supported within said compartment for holding a label at said opening, said label holder being provided with a guide adjacent said slot and being provided with a flange extending toward said front member at the side of said opening opposite said slot.

75 6. In an article of the class described, a receptacle front member provided with a window opening, said front member having a marginal flange on one of its sides, a lining member mounted in spaced relation to said front member and having a portion engaging said marginal flange, one of said members being provided with a label-receiving opening adjacent said flange, and a label holder supported behind said window opening in the space between said members, and normally tending to move a label supported thereon toward said window opening.

80 7. In an article of the class described, a receptacle front member having a window opening therein, a lining member supported in spaced parallel relation therewith, certain of the edges of said members being in engagement to form a substantially closed chamber, except for a slot along a portion of one edge, and a label support held between said members having a flange extending toward said front member at the side of said window opening opposite said slot and an extension on the side opposite said flange, 85 said extension serving as a guide for a label inserted through said slot.

85 8. In an article of the class described, a metal receptacle front member having a window opening therein, a lining member supported in spaced parallel relation therewith, certain of the edges of said members being in engagement to form a substantially closed chamber, except for a slot along a portion of one edge, and a label support mounted between said members and having 90 flanges on three sides extending toward said front member, said support having an extension on its fourth side engaging said lining member at a place near said slot.

95 9. In an article of the class described, a sheet metal receptacle front member having a window opening therein, the material of said front member at said opening being formed into flanges extending rearwardly thereof, a lining member mounted in spaced parallel relation to said front member, certain of the edges of said members being brought into engagement to form a substantially closed chamber, except for a slot opening into said chamber, and a label holder 100 formed of resilient material and mounted on one of said members to hold a label inserted through said slot into said label holder against certain of the edges of the window flanges on said front member.

105 10. In an article of the class described, a sheet metal front member having a window opening therein, and a lining member engaging said front member, said lining member having a label supporting panel adjacent said window depressed into the space between the principal 110 planes of said members.

110 11. In an article of the class described, a sheet metal front member having a window opening therein, a lining member supported in spaced relation to said front member, said lining member having a portion depressed into position adjacent said window, and a label support mounted on the depressed portion of said lining member in the space between the principal planes of said members.

12. In an article of the class described, a sheet member, and a label support mounted adjacent metal front member having a window opening therein, a lining member supported in spaced relation to said front member, said lining member having a portion depressed into position adjacent said window, said portion having a window therein in registry with said first window, and a label holder mounted on the depressed portion of said lining member on the surface thereof remote from said front member and in the space between the principal planes of said members.
13. In an article of the class described, a sheet metal receptacle front member having a window opening therein, a window frame attached to said front member in said window opening, a lining member slightly spaced from said front
14. In an article of the class described, a sheet metal receptacle front member having a window opening therein, a window frame attached to said front member adjacent said window and extending therethrough, a lining member slightly spaced from said front member, and a label support mounted adjacent said window between the principal planes of said members to support a label in engagement with certain of the edges of said frame.
